UNITED STATES PATENT OFFICE.

JOHN R. McKEOWN, OF TORONTO, ONTARIO, CANADA.

HEAT-BOX.

1,319,781.

Specification of Letters Patent. Patented Oct. 28, 1919.

Application filed January 26, 1918. Serial No. 213,998.

To all whom it may concern:

Be it known that I, JOHN R. McKEOWN, of the city of Toronto, in the county of York, in the Province of Ontario, in the Dominion of Canada, have invented certain new and useful Improvements in Heat-Boxes, and do hereby declare that the following is a full, clear, and exact description of same.

10 This invention relates to heat boxes or chambers particularly adaptable to be used as incubators, or for the purpose of raising bread, and such purposes where a steady heat is required, and has for its objects to 15 provide such a device adapted to be heated by fluid circulation around the walls thereof, and to provide simple and efficient means for carrying such an object into effect.

Further objects subsidiary to or resulting 20 from the before-mentioned main objects or from the construction of the invention as it may be carried into effect, will become apparent as the invention is hereinafter further disclosed.

25 As a means of carrying the said invention into effect, I may provide a heat chamber with double lateral walls, between which fluid in a heated state may circulate, a suitable heater being connected to the chamber 30 or chambers formed between the said double wall, the said chamber being suitably insulated to prevent the escape of heat outwardly from the fluid therewithin, whereby all, or practically all, of such heat will be 35 directed into the heat box as required; and it is preferred to divide the fluid chamber into upper and lower passages by means of a wall extending across the same intermediate of the height thereof, the said wall terminating at a desirable distance from the 40 extremities of the said chamber, whereby the passage of heated fluid from the upper side to the underside of the said wall will be permitted, all of which is more particularly described and ascertained in and by 45 the following statement having reference to the example illustrated in the accompanying drawing, in which:

Figure 1 is a broken perspective view of 50 a heat box constructed in accordance with this invention:

Fig. 2 is a sectional plan view of the same, and

Fig. 3 is a vertical section of the rear end 55 of the same showing the heater connection thereto.

Similar characters of reference indicate similar parts in the several figures of the drawing.

A is a heat box having a lateral wall 1 which, in its preferred form, is substantially curved at the rear of the box, whereby in plan it may be said to be U-shaped, a door 2 extending between the extremities of the said lateral wall A and serving, when closed, 60 with the top 3 and bottom 4 of the heat box to form an inclosed receptacle for any article which it may be desired to subject to a continuous heat, 5, 5 being slides upon which, for example, an incubator tray may 65 be accommodated. 6 is a further wall parallel to the aforesaid wall 1, and forming an inclosed chamber therebetween, and 7 is a still further and outer wall extending around the said wall 6 and inclosing a layer 70 of heat-insulating material 8, such as asbestos. The chamber between the walls 1 and 7, which walls will be hereinafter referred to in combination as a double wall, is preferably divided into upper and lower 75 passages, which are indicated as 9^a and 9^b respectively, by a transverse partition 10, terminating at a desirable distance from the forward extremities of the said double wall, whereby communication is established 80 between the said upper and lower passages 9^a and 9^b. 11 is an inlet to the said chamber, through which fluid, preferably preheated, may be introduced to the said chamber, and 12 is a heater having conduits 13 and 14 85 connecting the same with the upper and lower passages 9^a and 9^b respectively in the said double wall, whereby a convection current may be secured, as will be readily understood. With a device of this type, heat 90 within the box may be readily secured by the pouring of preheated fluid into the chamber between the walls 1 and 6, such heat being thereafter maintained by means of the heater 12, and any well-known means 95 may be employed to effect the regulation of the heater; and it will be understood that changes in the exterior temperature will not easily affect the temperature within the said heat box, owing to the heat being secured 100 from the walls thereof, through which, in the old types of heat boxes, the heat more or less escaped, and furthermore, in the device now proposed, it will be comparatively easy to retain a steady temperature owing to the 105 limitations of temperature to which fluids may be raised in the surrounding walls, even 110

though the temperature of the heating medium may become excessive.

This invention may be developed within the scope of the following claims without departing from the essential features of the said invention, and it is desired that the specification and drawing be read as being merely illustrative and not in a limiting sense except as necessitated by the prior art.

10 What I claim is:—

1. A heating device of the character described comprising a box like body having a top, a bottom, a door and a side wall, said side wall being U-shaped in plan and doubled to form a U-shaped hot water receiving chamber, a horizontal partition dividing said chamber into upper and lower compartments and terminating short of the ends of the side wall to allow communication between the compartments, a filling inlet communicating with the medial portion from one of said compartments, pipes leading from the medial portions of both of said compartments and a heating chamber with 25 which said pipes communicate.

2. A heating device of the character described including a box like body comprising

ing a bottom, a top, a side wall U-shaped in plan having its upper and lower edges joined with the top and bottom, a door for the body, another side wall surrounding and spaced from the outer face of the first mentioned side wall and secured to the upper and lower edges thereof to provide a hot water receiving chamber an outer side wall 35 surrounding the last mentioned side wall, a layer of heat insulated material between the last mentioned side walls, a horizontal partition arranged in the chamber and terminating short of the ends of the side walls 40 to provide upper and lower communicating compartments, a filling inlet extending through the medial portions of the outer side wall and communicating with one of the compartments, pipes leading from the 45 medial portions of the compartments and a heating chamber associated with the outer ends of the pipes.

Signed at the city of Toronto, in the county of York, in the Province of Ontario, 50 in the Dominion of Canada, this 22nd day of January, 1918.

JOHN R. McKEOWN.
